ABSTRACT OF THE DISCLOSURE

A novel surface active agent comprising a phosphorous triester-type compound having the following formula:

wherein R_1 is a conventional nonionic surface active agent residue to which ethylene oxide or both ethylene oxide and propylene oxide is added, and R_2 and R_3 are a conventional nonionic surface active agent residue to which ethylene oxide or both ethylene oxide and propylene oxide is added or an alkyl group having 8 to 22 carbon atoms and its preparation are described. The surface active agent is superior in surface activity, heat-resisting stability and a reduced foaming property.

This invention relates to a novel surface active agent and a method of preparing the same.

An object of the present invention is to provide a novel surface active agent which has superior surface activities, a heat-resisting stability and a reduced foaming property.

Other objects and advantages of the present invention will become apparent from the following description.

The surface active agent of the present invention comprises a compound having the following general formula:

wherein R_1 is a conventional nonionic surface active agent residue to which one or more moles of ethylene oxide or one or more moles of both ethylene oxide and propylene oxide is added, and R_2 and R_3 are a member selected from the group consisting of a conventional nonionic surface active agent residue to which one or more moles of ethylene oxide or one or more moles of both ethylene oxide and propylene oxide is added and an alkyl group having 8 to 22 carbon atoms.

The above conventional nonionic surface active agent includes, for example, (1) a nonionic surface active agent of such a type as an addition product of 1 to 100 moles of ethylene oxide or 1 to 100 moles of both ethylene oxide and propylene oxide to one mole of higher alcohol having 8 to 22 carbon atoms such as octyl alcohol, lauryl alcohol, coconut alcohol, cetyl alcohol, stearyl alcohol, oleyl alco-

2

hol, tridecyl alcohol, etc.; (2) that of such a type as an addition product of 1 to 100 moles of ethylene oxide or 1 to 100 moles of both ethylene oxide and propylene oxide to one mole of alkyl phenol containing an alkyl group having 4 to 22 carbon atoms such as butyl phenol, octyl phenol, nonyl phenol, dodecyl phenol, dinonyl phenol, etc.; (3) that of such a type as an addition product of 1 to 100 moles of ethylene oxide or 1 to 100 moles of both ethylene oxide and propylene oxide to one mole of higher fatty acid having 8 to 22 carbon atoms such as coconut fatty acid, lauric acid, oleic acid, stearic acid, palmitic acid, etc.; (4) that of such a type as an addition product of 1 to 100 moles of ethylene oxide or 1 to 100 moles of both ethylene oxide and propylene oxide to one mole of alkyl amine having 8 to 22 carbon atoms such as coconut amine, lauryl amine, stearyl amine, hexadecyl amine, etc.; (5) that of such a type as an addition product of 1 to 100 moles of ethylene oxide or 1 to 100 moles of both ethylene oxide and propylene oxide to one mole of higher fatty acid amide having 8 to 22 carbon atoms such as lauric acid amide, stearic acid amide, palmitic acid amide, oleic acid amide, etc., and (6) that of such a type as an addition product of 1 to 100 moles of ethylene oxide or 1 to 100 moles of both ethylene oxide and propylene oxide to one mole of aryl phenol having 2 to 5 benzene rings such as p-phenyl phenol, benzyl naphthol and tri-ethylbenzene phenol, etc.

The surface active agent of the present invention is prepared by the following method:

30 The compound wherein all of R_1 , R_2 and R_3 in the above formula are conventional surface active agent residues, is prepared by reacting one mole of triaryl phosphite or trichloroaryl phosphite with at least about 3 moles of a conventional surface active agent using a strong basic catalyst, which results in ester interchange of the former with the latter.

35 The compound wherein one or two of R_2 and R_3 in the formula are alkyl groups having 8 to 22 carbon atoms, is prepared by reacting one mole of triaryl phosphite or trichloroaryl phosphite with at least about three moles of both conventional surface active agent and higher alcohol, wherein the mole ratio of the surface active agent to the higher alcohol is approximately $\frac{1}{2}$ to 2, using a strong basic catalyst.

40 A strong basic catalyst, which is used in the present invention, includes, for example, metal alcoholates such as sodium methylate, potassium phenolate, etc.; quaternary ammonium hydroxides; inorganic strong bases such as sodium hydroxide, potassium hydroxide, etc.; and alkali metals such as sodium, potassium, etc. As to the proportion of the basic catalyst, from 0.001 to 0.20 mole based on the moles of triaryl phosphite or trichloroaryl phosphite is preferable.

45 Triaryl phosphite or trichloroaryl phosphite, which is used in the present invention, includes, for example, tri-phenyl phosphite, tri-p-cresyl phosphite, tri-o-cresyl phosphite, tri-m-cresyl phosphite, tri-butylphenyl phosphite, tri-o-chlorophenyl phosphite, tri-p-chlorophenyl phosphite, tri-m-chlorophenyl phosphite, etc.

50 Conventional surface active agents, which are used in the present invention, are listed hereinbefore.

55 The higher alcohol, which is used in the present invention, is a saturated or unsaturated alcohol containing an

alkyl group having 8 to 22 carbon atoms which includes, for example, octanol, decanol, lauryl alcohol, myristyl alcohol, palmityl alcohol, cetyl alcohol, stearyl alcohol, oleyl alcohol, coconut alcohol, tridecyl alcohol, etc.

The ester interchange reaction of the present invention is effected at a temperature of 100 to 250° C. under atmospheric or reduced pressure, preferably a reduced pressure of 1 to 10 mm. Hg.

The surface active agent of the present invention has several predominant characteristics; first, it exhibits heat-resisting stability. Particularly, in the case where a non-ionic surface active agent, which is used as raw material, has saturated alkyl group and does not contain amino or amide group and contains 1 to 15 mols of either ethylene oxide or both ethylene oxide and propylene oxide, and where the higher alcohol, which is used as the raw material, has a saturated alkyl group, the resultant surface active agent exhibits less weight-reduction due to volatilization and also less change in hue even if it is left in the atmosphere at a high temperature exceeding 200° C. for a long time. Such a high heat resistance could not be expected in conventional surface active agents. Secondly, all of the surface active agent of the present invention has remarkably reduced foaming property in comparison with conventional surface active agents.

The surface active agent of the present invention is widely used as an emulsifier, solubilizer, detergent, dispersant, lubricant, antistatic agent, defoaming agent, etc. in the similar manner to that of conventional surface active agents. Among the surface active agents of the present invention, those wherein 1 to 20 moles of ethylene oxide or both ethylene oxide and propylene oxide is added to the conventional surface active agent residue are the most practical.

Further, the surface active agents have more specific uses as, for example, an antistatic agent and lubricant for synthetic fibers which are treated at a high temperature, additive for metal-lubricating oil which has antioxidative property, internal antistatic agent for synthetic molded article or synthetic fiber, and purifying and dispersing agent for engine oil, etc.

In order that the invention may be more fully understood, examples are given below.

EXAMPLE 1

490 g. of poly[8]oxyethylene lauryl ether, which were prepared by adding an average of 8 moles of ethylene oxide to 1 mole of commercial lauryl alcohol, 103 g. of triphenyl phosphite and 0.5 g. of potassium hydroxide were charged into a four neck flask equipped with an agitator, thermometer and vacuum apparatus. The resultant mixture was heated to 130° C. and stirred for one hour and then, treated under a reduced pressure of 10 mm. Hg at a temperature of 130 to 180° C. for three hours to effect dephenolization. 93 g. of phenol was distilled off. After filtration, colorless and transparent oily product having a specific gravity of 1.014 (25/4° C.) was obtained. The resultant product proved that it did not have an infrared absorption spectrum corresponding to an OH group. The product was tested as will be described later.

A numerical value within the brackets [] indicates an average number of moles of ethylene oxide added to the conventional surface active agent.

EXAMPLE 2

980 g. of poly[15]oxyethylene-poly[2]oxypropylene lauryl ether, which were prepared by adding an average of 15 moles of ethylene oxide and an average of 2 moles of propylene oxide to 1 mole of commercial lauryl alco-

hol, 103 g. of triphenyl phosphite and 0.5 g. of potassium hydroxide were treated in the same manner as described in Example 1 to effect dephenolization. 93 g. of phenol was distilled off. After filtration, a white waxy product was obtained. The product proved that it did not have an infrared absorption spectrum corresponding to an OH group. The product was tested as will be described later.

EXAMPLE 3

162 g. poly[9]oxyethylene lauryl ether, 138 g. of tri(o-chlorophenyl) phosphite and 0.2 g. of sodium hydroxide were charged into a four neck flask equipped with an agitator, thermometer and vacuum apparatus. The mixture was heated to 130° C. and then treated at a temperature from 130 to 180° C. under a reduced pressure of 5 mm. Hg for two hours to effect dephenolization and to distill off 42 g. of o-chlorophenol. Further, 126 g. of commercial lauryl alcohol were added to the above product. Then, the mixture was treated at a temperature from 180 to 250° C. under a reduced pressure of 5 mm. Hg for 4 hours to effect dephenolization. 84 g. of o-chlorophenol were distilled off. After filtration, colorless and transparent oily product having a specific gravity of 0.952 (25/4° C.) was obtained. The resultant product proved that it did not exhibit an infrared absorption spectrum corresponding to an OH group. The product was also tested as will be described later.

EXAMPLES 4-22

Methods similar to those described in Examples 1 to 3 were repeated except that starting materials and reacting conditions were as listed in Table 1 and Table 2, respectively.

All of the resultant products proved that they did not have an infrared absorption spectrum corresponding to an OH group. They were tested as will be described later.

Properties of the surface active agent of the present invention is hereinafter described.

(1) Surface tension, foaming property and heat-resisting stability

Properties of the products obtained in the above Examples 1 to 22 were determined. Results are given in Table 3 in comparison with conventional surface active agents.

25 Each of the mixtures of 30 parts by weight of the product in Example 1 and 70 parts by weight of refined mineral oil having a viscosity of 100 sec., of 30 parts by weight of the product in Example 15 and 70 parts by weight of refined mineral oil having a viscosity of 100 sec., and of 30 parts by weight of the product in Example 20 and 70 parts by weight of refined mineral oil having

3	33.5	33.0	190	190 r	10.5 -----	28.5		
4				r	2.9 -----	4.7		
5				r	1.8 -----	5.2		

¹ Control surface active agents are as follows:

- 1=poly[8]oxyethylene lauryl ether,
- 2=poly[8]oxyethylene octyl phenol ether,
- 3=poly[10]oxyethylene oleyl phenol ether,
- 4=poly[20]oxyethylene sorbitan tristearate,
- 5=poly[10]oxyethylene stearic acid amide.

² Surface tension was determined by a Du Nouy-type tension meter at 25° C.

³ Foaming properties were tested by Ross Meiles method at 40° C. using 0.25% by weight solution of surfactant.

Height of foam was determined immediately after and 3 min. after dripping.

⁴ Heat-resisting stability was tested by the following method; 30 g. of each sample surfactant were charged into a test tube (36 mm. x 200 mm.). After the sample was left in a thermostat at 220° C. for 6 hours without corking the test tube, decrement of the sample by volatilization and hue change of the sample were measured. Marks "n," "s," "c" and "r" designate "no change," "slightly changed," "changed" and "remarkably changed," respectively.

a viscosity of 100 Saybolt sec. could be uniformly dispersed in water at room temperature.

In the case where a mixture of 30 parts by weight of the product in Example 6 and 70 parts by weight of butyl stearate was heated to 50° C. and then, 150 parts by weight of warm water at 60° C. were poured into the heated mixture while being gradually stirred, a uniform emulsion was obtained.

Further, in the case where a mixture of 5 parts by weight of the product in Example 8 and 50 parts by weight of spindle oil having a viscosity of 150 sec. was heated to 80° C. and then, 35 parts by weight of warm water at 80° C. were gradually poured into the heated mixture while being stirred, a uniform and stable emulsion of w/o type was obtained.

Still further, in the case where 2 g. of the product in Example 14 was dissolved in 30 g. of water and then, 70 g. of commercial gasoline was dripped for 10 min. while being violently stirred, a highly viscous emulsion having a viscosity of 20,000 cps. at 20° C. was obtained. The resultant emulsion was found to be useful for printing.

(3) Detergency

As to the products in Examples 1, 4, 5, 10 and 17, detergency was tested by a detergency testing procedure determined by the Japan Oil Chemists Society using a Launder-O-Meter under the following conditions; temperature, 40±1° C.; time, 30 min.; 20 steel balls each having a diameter of 1/4 inch were used; number of revolutions, 40 r.p.m.; concentration of surfactant, 0.3% by weight. Spectral reflectance was determined by a spectrophotometer made by Hitachi Seisakusho, Japan, wherein a measured value of magnesium carbonate specimen was 100 in relation to the standard value. Detergency efficiency was calculated from the following equation:

$$\text{Detergency efficiency (percent)} = \frac{D-S}{O-S} \times 100$$

where;

D=Detergency efficiency of deterged fabric,
S=Detergency efficiency of stained fabric,
O=Detergency efficiency of original fabric.
Results are given in Table 4.

TABLE 4

Surfactant	Detergency efficiency
Product in Example:	
1	75.6
4	77.9
5	78.0
10	72.5
17	73.6

(4) Antistatic property

Antistatic properties of the products in Examples 1-7, 65 and 9-22 were tested as follows:

Taffetas were prepared from polyethylene terephthalate filament ("Tetoron," Toray Co., Japan) and nylon-6 filament (Toray Co., Japan). Each taffeta was dipped in an ethyl alcoholic solution containing 1% by weight of sample surfactant at 30° C. for 1 minute. After squeezing to pick-up 70% OFW, the taffeta was air-dried. Antistatic property of the resultant taffeta was measured by a Textile Electrostaticscope (made by Denpa Kogyo, Japan) at 20° C. and 65% R.H. The results are given in Table 5. 75 wherein *n* is an integer of 1 to 20.

TABLE 5

Surfactant	Tetoron	Nylon
Product in Example:		
1	1.5×10 ⁸	7.7×10 ⁸
2	7.2×10 ⁸	4.8×10 ⁸
3	2.4×10 ⁸	1.0×10 ⁹
4	1.7×10 ⁸	2.5×10 ¹⁰
5	2.7×10 ⁸	3.4×10 ¹⁰
6	3.2×10 ⁸	1.5×10 ⁹
7	2.7×10 ⁸	1.0×10 ⁹
9	2.7×10 ¹⁰	3.5×10 ¹²
10	2.6×10 ⁸	3.8×10 ⁸
11	6.8×10 ⁸	2.2×10 ¹⁰
12	8.9×10 ⁷	1.3×10 ⁹
13	1.3×10 ⁸	9.9×10 ⁸
14	2.3×10 ⁸	2.6×10 ⁹
15	7.6×10 ⁸	1.3×10 ¹⁰
16	7.3×10 ⁷	2.8×10 ⁸
17	1.3×10 ⁸	2.7×10 ¹⁰
18	3.8×10 ⁸	4.6×10 ⁸
19	2.7×10 ⁸	2.3×10 ⁹
20	6.4×10 ⁸	9.2×10 ⁸

22	1.1×10 ⁹	8.6×10 ⁸
Blank	3.5×10 ¹⁴	1.5×10 ¹⁵

Further as to the products in Examples 1-3, 13, 18, 19 and 20, antistatic property was tested by the following method:

0.2 g. of each product was added to 100 g. of polyethylene ("Sumikasen L-702" made by Sumitomo Chemical, Japan) and the mixture was roll-milled at 130° C. for 10 min. and then, subjected to press molding at 150° C. for 10 min. to form a sheet having a thickness of 2 mm.

When the resultant sheet was superposed above the ash of cigarette at a distance of 1 cm. after it was rubbed with nylon cloth ten times, the ash was not attracted to the sheet, resulting in proof that the sheet contained a favorable antistatic property. On the other hand, in the case of the sheet which did not contain the product, the ash was attracted to it.

Color of both sheets did not change through the above press moulding.

What we claim is:

1. A surface active compound having the formula

wherein R₁, R₂ and R₃ are each the same residue of a nonionic surface active compound, said residue having a formula selected from a member of the group consisting of

and

wherein in each of said formulas, *n* is an integer of 1 to 20.

2. A surface active compound according to claim 1 wherein each of R₁, R₂ and R₃ is represented by the formula

3. A surface active compound according to claim 1 wherein each of R₁, R₂ and R₃ is represented by the formula

wherein n is an integer of 1 to 20.

4. A surface active compound according to claim 1 wherein each of R₁, R₂ and R₃ is represented by the formula

wherein n is an integer of 1 to 20.

5. A surface active compound according to claim 1

5

wherein each of R₁, R₂ and R₃ is represented by the formula

wherein n is an integer of 1 to 20.
